Attorney

UNITED STATES PATENT OFFICE.

BRUNO MARTIN, OF SAGINAW, MICHIGAN.

BLOWTORCH.

Application filed October 22, 1926. Serial No. 143,360.

This invention relates to certain new and useful improvements in blow torches, and has for its objects among others to improve upon prior forms of torches in various ways 5 as will hereinafter appear.

The present invention has for its objects among others to provide simple and efficient means to prevent escape of vapors and thus safeguard against explosions.

10 It has for a further object to provide simple and efficient means for preventing the escape of pressure in the tank and at the same time insure that this vapor pressure cannot escape to the atmosphere, but will circulate 15 back to the tank.

It has for still another object to provide means whereby the gasoline is prevented 20 from going back into the pump in case the valve does not work properly, by taking away the pressure on the inside of the tank 25 pressure tube.

These and other objects of the invention will hereinafter appear and the novel features thereof will be specifically defined by 25 the appended claims.

The invention, in its preferred form, is clearly illustrated in the accompanying drawings, which, with the numerals of reference marked thereon, form a part of this 30 specification, and in which

Figure 1 is a side elevation of a blow torch constructed in accordance with my present invention.

Figure 2 is a substantially central vertical section through the same, with parts shown in elevation, and portions broken away.

Like numerals of reference indicate like parts in the different views.

40 Referring to the drawings:

The parts indicated in dotted lines in Figure 1 form no part of the present invention and as they may be of any well known type, or such other as may perform the desired 45 functions, and are well understood, being herein shown merely for the purpose of showing the application of the present invention, which resides in the structure shown in enlarged section in Figure 2 and 50 as applied in Figure 1, no detailed description of said parts as shown in dotted lines is necessary, further than to merely state that 1 indicates the tank, 2 the torch, 3 the control valve therefor, 4 the pipe supporting the torch and the cup 5, as usual,

it being understood that the pipe 4 communicates with the interior of the tank.

The present invention, as hereinbefore stated, resides in the novel construction and arrangement of parts as shown in full lines 60 in Figure 1 and in detail in Figure 2, to which latter attention is now directed, and in which 6 is a member, a casting preferably, comprising a lateral member 7 having at one a threaded portion 8 adapted to be 65 screwed into the wall of the tank, this member 7 having a passage 9 therethrough as seen in Figure 2, the other end of said member having the upright terminal 10 communicating with the passage or bore 9 and 70 being threaded as seen at 11 for the reception of the lower threaded end 12 of the pump barrel, as shown in Figure 2.

The pump may be of any well known or approved form adapted to the purpose, 14 75 being the piston, 15 its rod, and 16 a packing disc or washer for the usual purpose, 17 being a spring around the piston rod and bearing upon the upper face of the piston 14. The piston of the pump is provided with the 80 usual ring or other provision 18 by which the piston is reciprocated, 19 being the cap to the pump barrel.

20 is an upright member rising from the lateral member 7 of the member 6 and having the bore or passage 21 the upper end of which communicates with the upper lateral passage 22, which, in turn, communicates with the vertical bore or passage 23 in the vertical portion 24 of the casting 6, as 90 shown clearly in Figure 2.

Communication between the passages 22 and 23 in the casting is controlled by the air valve 25 disposed within the depending member 26 of the casting 6 and adapted to 95 be actuated by means of the handle 27 on its stem 28.

The upper end of the pump barrel is sustained in position by being received within the ring or the like 29 on the lateral arm 30 100 of the casting 6.

The casting 6 has further the lateral arm or nipple 31 in which is screwed one end of the lateral pipe 32, the other end of which is screwed into the tank 1 near the upper end 105 of the latter.

The upper end of the casting 1 terminates in the filling cup 33, the stem 34 of this cup being internally threaded as seen in Figure 2 and within this threaded bore is screwed the 110

lower threaded end of the valve rod 35, the latter being tubular and carrying the valve 36 having a washer 37, the valve rod having a handle 38 which valve rod passes loosely through a convex cap 39 seated within the filling cup, and the outer cap 40 resting upon the upper edge of the filling cup and having its lower edge extended below said edge.

On top of the cap 40 is shown a washer or plate 41 against which bears the spring 42 surrounding the rod 35. The valve rod 35 has a lateral opening or openings 43, see Figure 2, to allow of the return to the tank of any vapor that may accumulate in the passage filling cup, through the said passage 43.

The parts just described in detail having been connected up with the tank in the manner shown their purpose is as follows:—

20 The caps 39 and 40 are held closed by the spring so securely the escape of vapors is prevented and this provides a safeguard against explosions which are apt to occur when the gasoline vapors are allowed to escape.

When ready to use the torch the air valve 25 is opened and a few strokes of the pump given and then the valve closed. This takes away the pressure on the interior of the tank 30 pressure tube; which is a very important factor for thereby the gasoline is kept from going back into the pump, in case the valve does not work properly.

Upon reference to Figure 2 there will be seen some holes 43 in the screw threaded portion of the rod 35. By loosening the screw on the filling cup slightly, say, about a quarter of an inch, just sufficient to allow of the escape of the vapor into the filling cup 40 and thence back into the tank. As soon as this is done the flame will be extinguished quickly, and nothing else has to be done until it is desired to use the torch again.

While the essential features of the present invention are as above outlined, it is evident that the means of accomplishing the ends in view may be modified without departing from the invention or sacrificing any of its advantages. I therefore do not wish to restrict myself to the particular construction, arrangement, and shape of the parts, but reserve the right to make such changes, variations and modifications as come properly within the scope of the appended claims.

55 For instance, as seen in Figure 1 I sometimes may provide an additional cup 50 located on the pipe 4 which connects the tank with the burner. This, it will be noticed, is located just under the drip pan and receives

60 that gasoline that overflows from the said drip pan, thereby giving a quicker heating generator and stronger heating power to the burner, and also lessens the smoking.

What is claimed as new is:—

65 1. In a blow torch, a filling cup, a closure

therefor, a supplemental closure, cooperating therewith, a valve rod passed through said closures, and a spring on the rod acting upon the outermost closure.

2. In a blow torch, a filling cup, a closure 70 fitted therein, a closure fitting over the top of said cup, a valve controlling the outflow from the said cup, the rod for said valve, and a spring acting on the outermost closure to safeguard against escape of vapors and hence 75 explosions.

3. A blow torch attachment comprising a casting having threaded extension for connection with a tank and an upright terminal for connection with a pump, an upright 80 tubular member rising from the extension and terminating in a lateral passage and vertical bore and a chamber connected therewith, and a stem and filling cup at the upper end of said casting and a lateral member for 85 cooperation with a pump barrel.

4. In a blow torch, the combination with the filling cup thereof, of multiple closures 90 therefor, one of which is within the other, and the outermost one bearing on the upper edge of the cup and means for putting said closures under compression to effectually prevent the escape of gasoline vapor.

5. In a blow torch, the combination with the filling cup thereof, of multiple closures 95 therefor, one of which is within the other, and the outermost one bearing on the upper edge of the cup means for putting said closures under compression to effectually prevent the escape of gasoline vapor, and means 100 controlled by the compression means to allow escape of the vapor from the filling cup back to the tank.

6. In a blow torch, the combination with the filling tube thereof, of multiple closures 105 therefor, one of which is within the other, and the outermost one bearing on the upper edge of the cup means for putting said closures under compression, to effectually prevent escape of gasoline vapor, and a valve 110 cooperable with the compression means, the stem of the said valve being provided with an opening to provide communication between the cup and the tank when the valve is raised.

7. In a blow torch, a member having a lateral pipe for connection with a tank, and a filling cup, a closure for the filling cup, a valve controlling the outlet from the filling cup and having a rod passed through said closure, and supplemental closure means within the said closure and within the cup and through which the valve rod loosely passes.

8. In a blow torch, a member having a lateral pipe for connection with a tank, and a filling cup, a closure for the filling cup, a valve controlling the outlet from the filling cup, the said valve having a rod projecting into the outlet and provided with openings 120

to allow the return of vapor to the tank, and supplemental closure means within the closure and within the cup and through which the valve rod loosely passes.

5. 9. In a blow torch, a member having a lateral pipe for connection with a tank, and a filling cup, a closure for the filling cup, a valve controlling the outlet from the filling

cup and having a rod passed through the said closure, a supplemental closure for the filling cup and through which said valve rod passes, an air pump supported from said member, and an air valve in the connection between the pump and the said member.

In testimony whereof I affix my signature.
BRUNO MARTIN.
